[57] CLAIM

The ornamental design for a stethoscope chestpiece, as
shown.

DESCRIPTION

FIG. 1 is a perspective view of a stethoscope chestpiece
showing our new design;

FIG. 2 is a top plan view thereof;

FIG. 3 is a left side elevational view thereof, the right
side elevational view being a mirror image;

FIG. 4 is a front elevational view thereof; and

FIG. 5 is a rear elevational view thereof.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 323,394
DATED : January 21, 1992
INVENTOR(S) : CASTO et al.

It is certified that error appears in the above-identified patent and that said Letters Patent is hereby corrected as shown below:

On the Title page,

Column 2, under DESCRIPTION

replace "FIG. 4 is a front elevational view thereof; and
FIG. 5 is a rear elevational view thereof."

with --FIG. 4 is a front elevational view thereof;
FIG. 5 is a rear elevational view thereof; and
FIG. 6 is a bottom plan view thereof.--

Signed and Sealed this

Seventeenth Day of August, 1993

Attest:

BRUCE LEHMAN
